SPECTACLE TYPE FLASHLIGHT

Robert P. Evans, Westwood, Mass., assignor to
Visual Research Incorporated, Boston, Mass., a
corporation

Application February 5, 1953, Serial No. 23,459

Term of patent 14 years

(Cl. D48—24)

To all whom it may concern:

Be it known that I, Robert P. Evans, a citizen of the United States, residing at Westwood, in the county of Norfolk, in the Commonwealth of Massachusetts, have invented a new, original, and ornamental Design for a Spectacle Type Flashlight, of which the following is a specification, reference being had to the accompanying drawing, forming a part thereof, in which:

Figure 1 is a top plan view of a spectacle type flashlight embodying my new design.

Figure 2 is a bottom plan view thereof the temples being partly broken away for convenience of illustration;

Figure 3 is a front elevational view thereof; and

Figure 4 is a side elevational view thereof.

I claim:

The ornamental design for a spectacle type flashlight, substantially as shown.

ROBERT P. EVANS.
